UNITED STATES PATENT OFFICE.

FREDERICK R. SUNDERMAN, OF NEWBURGH, NEW YORK, ASSIGNOR TO SUNDERMAN SAFETY CARBURETER CORPORATION, OF NEWBURGH, NEW YORK, A CORPORATION OF NEW YORK.

MULTIPLE-CYLINDER INTERNAL-COMBUSTION ENGINE.

1,087,151.

Specification of Letters Patent.

Patented Feb. 17, 1914.

Application filed April 6, 1912. Serial No. 688,854.

To all whom it may concern:

Be it known that I, FREDERICK R. SUNDERMAN, a citizen of the United States, and a resident of Newburgh, in the county of Orange and State of New York, have invented certain new and useful Improvements in Multiple-Cylinder Internal-Combustion Engines, of which the following is a specification.

10 My invention relates to multiple cylinder internal combustion engines, and it has its most needed application in engines having six or more cylinders, though its use is not to be limited to engines having this number 15 of cylinders.

The object of my invention is to increase the efficiency of multiple cylinder internal combustion engines, and the invention consists in the provision of apparatus for insuring a proper distribution and regulation of the flow of fuel through the branch fuel supply pipes leading from the carbureter to the different cylinders. In such engines, the branch fuel supply pipes leading to the cylinders are connected with the main pipe from the carbureter by means of some suitable junction piece, which pipes, from the standpoint of vapor fuel supply passages, are of considerable length.

30 Without the use of such apparatus as this invention provides, when the piston in any cylinder moved to draw in a charge of fuel, it would not only draw fuel from the carbureter, but would also draw fuel from the different branch pipes leading to the other cylinders, thus partially robbing these pipes of their former charge. This drawing of fuel into the cylinders from branch pipes leading to other cylinders, has far reaching effects on the quality of fuel finally drawn into the cylinders, which result in greatly decreasing the power of the engine. For instance, assuming that the engine is running and that one of the pistons is drawing 40 in a charge of gas, since the branch pipe to that cylinder was partly emptied by the previously operated cylinders, a part of the movement of the piston is consumed in filling the pipe leading to this cylinder. The 45 charge that thus finally reaches the cylinder is impoverished and of low density, due to the fact that it is partially drawn from the other branch pipes and through a pipe in which there is a partial vacuum or reduced

density. Another detrimental effect upon the 55 charge of hydrocarbon gas thus drawn back and forth from one branch pipe to another over the different curves and elbows, is that the hydrocarbon gas is partially stratified, or the liquid hydrocarbon partially separated 60 out from the gas, which further impoverishes it. While these troubles arising from the drawing of fuel back and forth through the different branch pipes are experienced in four-cylinder engines, they are 65 much more manifest in engines having six or more cylinders. This is due to the longer lengths of the branch pipes and the order in and rapidity with which the cylinders are fired, which causes a more rapid surging of 70 the vapors over more indirect and longer passages. In order to overcome these difficulties, I have provided check valves in the branch passages near their junction so that each cylinder will draw its entire charge directly from the carbureter. In the preferred form of my invention, the junction point of the branch pipes is near the carbureter and the check valves are located in the junction piece.

75 My invention will be more readily understood and further objects of the invention will more fully appear from the following description taken in connection with the accompanying drawings in which—

Figure 1 is a side elevation of a six-cylinder gas engine equipped with my invention; Fig. 2 is a vertical sectional view of the preferred form of my fuel distributor or regulator shown in Fig. 1; and Fig. 3 is an enlarged cross-sectional view taken on line a—a of Fig. 2.

80 Referring to the drawings, 1 is the base of a gas engine on which cylinders 2, 3, 4, 5, 6 and 7 are mounted.

85 8 is a carbureter connected to the cylinders through main fuel supply pipe 9, junction piece or connection 10, which, in the present form of my invention, constitutes the fuel distributor or regulator, and branch fuel 90 supply pipes 11 to 19, inclusive.

95 Referring to Fig. 2, the fuel distributor is provided with an opening 20 leading to the carbureter 8, and with three separate openings or passages 21, 21', 21'' with which 100 the branch pipes 11, 14 and 17 connect, and these passages or openings 21, 21', 21'' are provided with seats 22, 22', 22'' on which

seat ball check valves 23, 23', 23''. These seats are preferably located at the lower ends of the openings 21, 21', 21'', and the check valves are preferably in the form of 5 balls and made of fiber in order to decrease the hammering action and noise which would result if metallic balls were used, and which would be more marked if ordinary disk check valves were used. Aside from the 10 noise which would result in the use of the ordinary disk form of check valves, the continual hammering of such valves would render them liable to be frequently broken.

In the preferred form of my invention, as 15 shown in Fig. 2, branch supply pipes 11 and 17 are arranged at an angle of 45 degrees and the inner contour or chamber portion of the fuel distributor presents a smooth unobstructed surface to the flow of gases, thus 20 avoiding any pocketing or eddy currents. When the branch pipes are arranged at an angle in this manner, I provide guides 24, 24' for the end balls 23, 23'', as more fully shown in Fig. 3.

25 In the operation of a six-cylinder engine as formerly constructed without the use of the present invention, cylinder 2 would first be fired drawing its fuel through branch pipe 11 from the carbureter and from 30 branch pipes 14 and 17, thus robbing these pipes of their former charge; then cylinder 6 would be fired, drawing its fuel through partly emptied branch pipe 17 from the carbureter and from pipes 14 and 11; then 35 cylinder 3 would be fired, drawing its charge through partly emptied branch pipe 11 from the carbureter and from pipes 14 and 17; then cylinder 7 would be fired, drawing its supply through pipe 17 as did 40 cylinder 6, and then cylinders 4 and 5 in order would be fired. Whereas, when the engine is equipped in accordance with my invention, each cylinder draws its entire 45 charge of rich fuel directly from the carbureter while the check valves to the other cylinders keep their branch pipes closed.

I have shown by actual experiment that a six-cylinder gas engine equipped with a fuel distributor or regulator according to my invention, will have its power increased over 50 25 per cent. above its maximum output under the same conditions, but with the omission of the gas distributor. Aside from the great increase in output resulting from this 55 invention, it is shown by actual experiments that the engines are much more readily started. Considerable difficulty has heretofore been experienced in starting up six-cylinder engines, whereas very little effort 60 is required when such engines are equipped with this invention, and this is believed to be due to the fact that each of the branch supply pipes, after the engine has been turned over once, or without turning it over at all 65 if it has been recently used, will contain a

full charge of rich fuel ready to be drawn into the cylinder.

While I have described my invention in detail in connection with what I believe to be its preferred form, it will be obvious to those skilled in the art that many changes in the construction, shape and location of the parts may be made without departing from the spirit of my invention, and that it will be immaterial to my broad invention if 70 the check valves be made of different types from that shown, or if they be located at other points than in the junction or connecting pieces for the different supply pipes; and I do not wish to be understood as limiting myself to any features other than as indicated in the appended claims. 75

Having now fully described my invention, what I claim as new and desire to secure by Letters Patent, is:—

85 1. In an internal combustion engine, the combination of a carbureter, a plurality of cylinders, branch fuel supply passages between the carbureter and the cylinders terminating at the cylinders for conveying 90 fuel from the carbureter to the cylinders, and check valves in said branch passages at the carbureter end thereof, whereby fuel to any cylinder may be drawn from the carbureter through the corresponding 95 branch passage, but not from other branch passages equipped with check valves.

2. In an internal combustion engine, the combination of a carbureter, a plurality of cylinders, branch fuel supply passages between the carbureter and the cylinders terminating at the cylinders and branching 100 adjacent the carbureter, and check valves in said branch passages at the junction thereof.

3. In an internal combustion engine, the combination of a carbureter, a plurality of cylinders, fuel supply pipes for conveying fuel from the carbureter to the cylinders, and a fuel distributor connected between the carbureter and the branch pipes and having 105 an opening to the carbureter and branch passages connecting with the pipes, and a check valve in each of two or more of said branch passages.

4. In an internal combustion engine, the 115 combination of a carbureter, a plurality of cylinders, branch fuel supply passages between the carbureter and the cylinders terminating at the cylinders for conveying fuel from the carbureter to the cylinders, and ball check valves in said branch passages at the carbureter end thereof, whereby fuel to any cylinder may be drawn from the carbureter through the corresponding branch 120 passage, but not from other branch passages 125 equipped with ball check valves.

5. In an internal combustion engine, the combination of a carbureter, a plurality of cylinders, fuel supply pipes for conveying fuel from the carbureter to the cylinders, 125

and a fuel distributor located adjacent the carbureter and having an opening to the carbureter and a plurality of branch passages connecting with the pipes, with a ball check valve in each of two or more of said branch passages.

6. In an internal combustion engine, the combination of a carbureter, a plurality of cylinders, fuel supply pipes for conveying fuel from the carbureter to the cylinders, and a fuel distributor connected between the carbureter and the branch pipes and comprising a chamber having an opening to the carbureter and branch passages connecting with the pipes, and ball check valves within said passages.

7. In an internal combustion engine, the

combination of a carbureter, a plurality of cylinders, fuel supply pipes for conveying fuel from the carbureter to the cylinders, 20 and a fuel distributor connected between the carbureter and the branch pipes and comprising a chamber having an opening to the carbureter and branch passages connecting with the pipes, and non-metallic ball check 25 valves within said passages, with guides for a plurality of said balls.

In testimony whereof, I have signed my name to this specification, in the presence of two subscribing witnesses.

FREDERICK R. SUNDERMAN.
